United States Patent Office

Des. 186,145
Patented Sept. 15, 1959

186,145

DESK PEN STAND

Bertram A. Strauss, Jamaica, N.Y., assignor to Columbia Pen & Pencil Co., Inc., Nassau County, N.Y., a corporation of New York

Application June 24, 1958, Serial No. 51,509

Term of patent 7 years

(Cl. D74—1)

Fig. 1 is a side perspective view of a desk pen stand showing my new design.

Fig. 2 is a side elevational view thereof as it appears separated from the base.

The dotted line illustration in Figure 1 of the base and parts of a pen are for illustrative purposes only.

I claim:

The ornamental design for a desk pen stand, as shown and described.
